UNITED STATES PATENT OFFICE.

LEWIS P. CONKLIN, OF RED BANK, NEW JERSEY.

ANTIRATTLING SASH-LOCK AND WINDOW-STOP.

1,153,763.

Specification of Letters Patent. Patented Sept. 14, 1915.

Application filed March 3, 1914. Serial No. 822,139.

To all whom it may concern:

Be it known that I, LEWIS P. CONKLIN, a citizen of the United States, and a resident of Red Bank, in the county of Monmouth and State of New Jersey, have invented certain new and useful Improvements in Anti-rattling Sash-Locks and Window-Stops, of which the following is a specification, reference being had to the accompanying drawings, forming a part of this specification.

This invention relates to certain new and useful improvements in locks employed in connection with window sashes; and the main object of my invention is to provide a sash lock which can be made to do service as a window stop.

Another object is to provide a self-locking sash lock positive in operation and of a simple and durable construction.

A still further object is to provide a sash lock which will hold the sashes to the window frame to prevent rattling of the sashes.

With these and other objects in view, the present invention consists in the combination and arrangement of parts as will be hereinafter more fully described and finally pointed out in the appended claims, it being further understood that changes in the specific structure shown and described may be made within the scope of the claims without departing from the spirit of the invention.

In the accompanying drawings forming a part of this specification and in which like numerals of reference indicate similar parts in the several views: Figure 1 shows a fragmentary portion of a window frame and sashes equipped with a lock and stop embodying my invention, the lock being shown as serving as a stop. Fig. 2 shows a sectional detail disclosing the device as serving as a window lock. Fig. 3 is a perspective view of the lock. Fig. 4 is a section on line 4, 4, of Fig. 1. Fig. 5 shows an inner view of a window frame and sashes disclosing the upper sash as being lowered for ventilating purposes. Fig. 6 shows a modification of the lock. Fig. 7 shows the lock as about to slide over one of the stops in the operation of closing the windows.

In my present invention, I provide a sash lock which is noticeable because of its extreme simplicity, and which is arranged to prevent the rattling of the sashes while the windows are open for ventilating purposes, the construction further being such that the sashes cannot be moved beyond a predeter-

mined distance either from within or without, without manually manipulating the lock, which however, automatically locks itself when the windows are closed.

In the drawings, the letter A, designates a suitable window frame including the inner batten B, the outer batten B' and the intermediate rail c, between which the window sashes slide.

The numeral 10 designates the top stile and 11 the side stiles of the inner window frame, while the numeral 9 designates the bottom stile and 8 the vertical stiles of the upper outer window sash.

In the use of my lock, the same is secured to the upper stile 10 of the inner window sash at a point opposite the vertical stile of the upper window frame in the manner shown in Fig. 1.

The lock comprises a flat plate 12, preferably made of spring steel one end of which is bent cylindrically to form the pin sleeve 13. Within this sleeve is held a staple 17 the points 18 of which are driven into the window stile to pivotally hold the sash lock in working position. The opposite end of the plate is continued in the form of a resilient V-shaped beak head. One branch of each V is formed by a flat section 14 which is bent obliquely outward while the other branch 15 is curved outwardly. The upper end of the curved branch is bent over to form the stop ledge 16 which ends in alinement with the body portion of the sash lock, as shown in Figs. 1 and 3.

In securing the lock to the sash, the operator places the sash lock in an upwardly inclined position, so that the convex surface 15 of the V branch of the beak head will rest against a vertical stile 8. The staple 17 is then driven into the top stile 10. In this position of the lock, should the lower sash be raised, or the upper sash be lowered, the beak head will be impinged upon the stile 8, the branch 14 finally binding upon the outer edge of the top stile 10, as shown in Fig. 1. In this position of the lock, the window sashes are firmly bound against the inner and outer battens and the window sashes can then only be advanced in exercising a force sufficient to overcome the frictional engagement of the beak head with the outer window stile.

In order to form a positive lock the outer window sash is provided along its vertical stiles with one or more stop pins 5, which

may be in the form of ordinary wood screws positioned in the path of the beak head.

As shown in Fig. 1, the lower sash has been raised such a height that the beak head 5 has been brought into contact with the stop

5. In this position of the lock, it is impossible to either raise the lower sash or lower the outer sash without first removing the stop pin 5, or lowering the inner sash and 10 manually carrying the lock upward to permit the beak head escaping over the stop pin. In Fig. 1, the stop pin 5 is located a suitable distance above the lower stile 9 of the upper window sash, so that the windows 15 can be adjusted for ventilating purposes..

In Fig. 2, the lock is arranged to serve in securely holding the sashes in locked position. In this instance the stop pin 7 is located immediately above the upper edge of 20 the outer portion of the beak head, so that a very slight movement of either sash will bring the pin 7 into collision with the beak head.

If desired, a wear plate 20 can be located 25 at the lower end of each vertical stile 8 upon which the beak heads rub. This wear plate 20 if desired may further have an upstanding lip 19 arranged to engage the V branch 14 of the sash lock. This upstanding 30 portion 19 performs a special function in that it draws the sash lock toward the wear plate bringing the scarf edges α , of the stiles 9 and 10 into contact, as clearly shown in Fig. 2.

35 Whenever the lock is made to do service as a window stop, as shown in Fig. 1, both sashes are forced against their battens to hold them in secured position, and preventing any rattling of the window 40 frames.

While it is impossible to open the windows as the beak head will collide with the stop pins 5, the windows can at any time be closed, as in closing them the beak heads 45 slide over the pins and finally drop below the same, so that the locks are self-closing or locking.

While I have shown and described the beak head as provided with the stop ledge 50 16, it should be understood that this ledge is not necessary, as the upper end of the V branch 15 can be made to engage the stop pins.

While I have described the plate 12 as being 55 continued in the obliquely extending branch 14, if desired the lock may be modified, as shown in Fig. 6, where the plate 12 is provided with the pin sleeve 13', while the opposite end is continued in a resilient 60 V-shaped beak head including the laterally curved branch 15' of the V from which extends the straight branch 14' of the V held

oblique to the major portion of the lock, as clearly shown. In the modification, the straight branch 14' ends at a point immediately below the under surface of the body portion of the sash lock. 65

It is of course understood that any number of stop pins 5. may be employed, and it might further be stated that I prefer using 70 two locks in connection with each window, as shown in Fig 5.

The lock as above described may be formed entire in one operation being 75 stamped from sheet metal.

The lock is simple and inexpensive in construction and both durable and efficient in operation, and the lock further can be adjusted upon a window sash, with ease, accuracy and despatch, and be made to do 80 service as a window stop and sash lock and an anti-rattling sash holder.

Having thus described my said invention what I claim as new and desire to secure by 85 United States Letters Patent is:—

1. A sash lock made of a single length of strap metal comprising a main flat portion from which extends at an angle a downwardly extending flat section from which is continued an outwardly curved portion ending in a stop ledge said stop ledge in turn ending in a plane in alinement with said main flat portion of the lock. 90

2. A sash lock including a plate provided with a resilient V-shaped beak head presenting a convex outward branch having a ledge in the plane of the plate the opposite end being bent to form a sleeve, and a securing staple within said sleeve. 95

3. A sash lock made of a plate one end of 100 which is bent to form a resilient V-shaped beak head presenting a convex branch outwardly curved the end of said branch being bent to form a stop ledge, means to removably hold said plate, and a pin in the path 105 of said ledge.

4. The combination with two window sashes of a lock secured to the upper stile of the lower sash and comprising a plate one end of which is bent to form a resilient 110 V-shaped head adapted to drop between the stiles with its vertex, one branch of said V being adapted to contact with the side stile of the upper window sash, means on the upper sash adapted to engage the V of the 115 lock whereby the V-shaped head jams the two sashes.

In testimony whereof I affix my signature, in the presence of two witnesses.

LEWIS P. CONKLIN.
